UNITED STATES PATENT OFFICE.

ROBERT WILLIAM DAVIS, OF HILTONIA, NEW JERSEY.

AERONAUTICAL PROPELLER.

1,386,458.

Specification of Letters Patent.

Patented Aug. 2, 1921.

Application filed July 17, 1918. Serial No. 245,347.

To all whom it may concern:

Be it known that I, ROBERT WILLIAM DAVIS, a citizen of the United States, and a resident of Hiltonia, in the county of Essex 5 and State of New Jersey, have invented certain new and useful Improvements in Aeronautical Propellers, of which the following is a specification.

This invention relates to improvements in 10 aeronautical propellers of the type that are rotated to produce a translatory movement of the structure of which they form a part, and it appertains more particularly to propellers adapted to exert a lifting or levitating effect upon that kind of heavier-than-air 15 apparatus known as helicopters.

One of the objects of the invention is to produce a propeller of the class mentioned having smooth, stream line effects and comparatively 20 large working surfaces or blades.

A further object is the production of a propeller of the type specified, capable of displacing large quantities of air at a relatively 25 low rotative speed and with an economical expenditure of power.

Another object is to provide a propeller of the nature set forth where lightness, strength and rigidity are attained with few and simple parts, adequately braced for use- 30 ful and practical service and yet amenable to low cost of production.

A still further object is the provision of a propeller of the character described composed of hollow members rotatively arranged 35 to conduct away the exhaust gases from a combustion driving motor as well as to direct the issuance thereof in a manner to prevent the air under the blades from moving radially outward.

Still another object is so to form a propeller of the kind referred to that the hot waste gases from the motor are utilized to prevent snow and ice from finding a lodgment upon the blades thereof.

Other objects and advantages of the invention will become apparent as the specification proceeds.

With the aforesaid objects in view, the invention consists of the novel combinations 50 and arrangements of parts hereinafter described in their preferred embodiments, pointed out in the subjoined claims, and illustrated on the annexed drawings, where-

in like parts are designated by the same reference characters throughout the several views.

In the said drawings:—

Figure I is a top plan view of this improved propeller, a part being broken away to show interiorly located details; 60

Fig. II is a front view of the propeller shown in the preceding figure, a part being also broken away for a similar purpose;

Fig. III is a sectional view taken on the line III—III of Fig. II, in the direction 65 pointed out by the arrows, parts being omitted and other parts broken away to show the interior construction;

Fig. IV is a sectional view taken irregularly on the line IV—IV of Fig. I looking 70 in the direction pointed out by the arrows;

Fig. V is a sectional view taken on the line V—V of Fig. IV, looking in either direction; and

Fig. VI is a fragmentary plan view of a 75 detail shown in Figs. I, II and III.

In these views the numeral 1 designates a driving shaft, operated by a combustion motor (not shown) either directly or through intermediary gearing in any approved manner. This shaft is preferably of stepped formation and includes a short reduced inner portion 2, a longer, further reduced middle portion 3, and a short still further reduced outer section 4. 80

Extending through the inner portions 1 and 2 of the said shaft is an axial bore 5 communicating with a similar but smaller bore 6 running through the outer portions 3 and 4. 90

A relatively large hub or inner carrier element 10 is rigidly affixed upon the shouldered portion 2 of the shaft, while a smaller hub or outer carrier element 11 is likewise secured upon the outermost section 4. A 95 pair of brackets 12 are formed with the said hub 10 and extend outwardly therefrom in opposite directions. One side of these brackets may be hollow to constitute conduits 13. The inner ends of the latter open into an annular chamber or recess 14 in the hub 10, while the outer terminals of the said conduits lead into the interior of sockets 15 at the extremities of the brackets. The said recess 14 communicates with ports 16 formed 100 through the wall of the portion 2 so as to

100

105

afford a passage between the axial bore of the shaft, the recess, the conduits and the said sockets 15.

The hub element 10 is preferably secured 5 to the portion 2 of the shaft by means of taper pins 18 which pass across the outer surfaces thereof and straddle the bore 5 in such a manner as to leave a clear passage through the same. The smaller hub 11 may 10 be held to the outer section 4 by a single taper pin 19, as indicated in Fig. I.

Rigidly supported in the sockets 15 are tubular members or arms 20 arranged to extend tangentially outward in opposite directions and communicating endwise with the extremities of the conduits 13, so as to provide a free passage therethrough. The ends of the sockets are tightly closed by plugs 21 to prevent the flow of air or gases.

20 Similar sockets 23 are formed on the opposite sides of the outer hub 11, although obviously the same could be made to pass centrally across this element. The extremity of the shaft bore 6 has fitted therein a plug 24 that shuts off all egress at that point. The lower end of this plug is located immediately above a recess 25 in the said hub, which recess communicates with the smaller bore 6 through ports 26 formed in the portion 4.

Secured rigidly in the sockets 23 is another pair of hollow members or arms 27 which extend outwardly therefrom in opposite directions, tangentially but closely approaching the center of the shaft. The ends of the said arms within the sockets 23 are provided with openings 28 that establish communication with the bore 6 through the ports 26 and the recess 25 hereinbefore referred to. The adjacent or inner ends of the hollow arms 27 are closed by tight fitting plugs 29. The members 20, 27 are arranged in pairs or sets, with the individual members of each pair or set disposed on lines 45 parallel to one another, though running outwardly in opposite directions. However, the sets themselves are not in parallelism, but as clearly seen in Fig. I, they diverge to the extent that the lower and upper sets 50 respectively occupy planes bisecting each other at an acute angle.

Carried by the outer half of the tubular members 20 and 27 is a plurality of frames 33, 33^a, 33^b, and 33^c which are curved substantially concentric with the shaft and having each tapered end portions. These frames are composed of I-sections having each a central web and top and bottom flanges 34, the webs of the different frames 60 being perforated at 35, except the innermost ones which are left imperforate. The tapered portions of the several frames are joined endwise by strips 36 and 36^a at the opposite upper and lower edges which constitute respectively the leading and trailing

edges of the blades or wings of the propeller. The ends of the several frames, and the strips adjacent thereto, are arranged on lines substantially parallel to the members 20, 27, respectively.

70

The frames may be cast of some such light metal as aluminum, or built up of strong wood or other suitable material, whereby lightness and strength are attained. Enveloping all of the several members and frames, are thin, light coverings 37, made of any preferred substance such as metal, textile fabric, or the like. The construction recited constitutes the wings or blades of the propeller, which may be hollow or chambered as described. Should it be desired to omit the hollow features of the blades it is only necessary to fasten a single sheet of metal to the bottom one of the flanges 34 of the said frames.

15

Within the outer covering 37, the inwardly facing sides of the hollow arms 20 and 27 are provided with apertures 38 disposed in graduated numbers along the said sides. The major part of these apertures are located between the frames 33 and 33^a, a lesser number between the frames 33^a and 33^b, and still fewer between the outer pairs of frames 33^b and 33^c. The outermost frames 33^c are shown as provided either with straight radially disposed apertures 35, at the extreme right hand portions of Figs. I and II, or with right angular apertures 39 formed through the bottom flange 34 of the said outer frame. One portion of the latter 90 named apertures extends parallel to the axis of the shaft 1 or at substantially right angles to the blade of the propeller. Both the apertures 35 and 39 are disposed at or near the outer perimetral edges of the blades, 105 transversely thereof. The escaping gases issue through these axially arranged apertures and form a curtain which acts as a barrier adapted to reduce if not entirely obviate such radial outward motion of the air 110 as may occur under the propeller blades. As indicated in Fig. IV the gases enter the blades oppositely at different levels.

100

The means for holding the frames 33, 33^a, etc., to the arms 20, 27 are shown in Figs. 115 I and II as consisting of wire lacing 40 and through rivets 41, either or both of which may be used.

A clamp ring 42 is fixed in an annular groove 42^a formed in the shaft 1 at a specified distance below the lower carrier element 10. This ring is provided with ears or lugs 43 from which extend pairs of guys 44 and 45. The guys 44 have their outer terminals attached to eyes 46 secured to the 120 under sides of the blades at the juncture of the frames 33^b with the arms 27, at a point about two-thirds the distance outwardly of the length of the propeller blades near the leading edges thereof.

130

The guys 45 have their outer ends anchored to eyes 47 located at the same side and distance out on the wings but adjacent to the trailing edges thereof. From 5 the eyes last named extend other guys 48, diverging in a plane at right angles to the axis of the shaft 1, to the sockets 15.

From the foregoing it will be seen the front or leading edges of the blades are 10 arranged approximately radial and move squarely against the air in a circular path, thereby producing the least friction against the blades as well as reducing the sidewise or lateral slip of the air under the same.

15 The difference in pitch is attained by having the upper arms 27 closely disposed adjacent to the center of the shaft while the lower arms 20 are considerably offset therefrom.

20 It will be noted that the lower arms 20 which are subjected to compression strain are braced by the guys 48, in the same plane as themselves, as well as axially by the guys 45. The points of attachment of the latter 25 guys are behind and also below the guys 48. Both sets of these guys are attached to their anchorages in advance of the arms themselves and in the direction of rotation.

The upper arms 27 which are primarily 30 exposed to bending strains are guyed to the inner portion of the shaft in the same manner as the arms 20, namely, axially and below the same, but with the difference that in this case the guys 44 are behind the arms.

35 The strains on all of these members are arranged to be transmitted by the several pairs of guys 44, 45 and 48 inwardly of the shaft as close as possible to its point of support. The pushing strain from the arms 40 20 is carried to the arms 27 by the frames 33, 33^a, etc., and produces a lifting stress on the latter arms which in turn is taken care of by the said guys 44.

The exhaust gases from the internal combustion motor which drives the propeller, 45 may enter the hollow shaft endwise thereof, or can be admitted through apertures 51, formed in the sides of the shaft 1, Fig. III. Surrounding these apertures is a sleeve 52 that may also serve as a bearing, and to 50 which a pipe 53 leading from the motor outlet is connected. Direct communication is thereby had with the alined bores 5, 6, ports 16, 26, recesses 14, 25, conduits 13, 55 openings 28, hollow arms 20, 27, and internal and external apertures 38 and 39, respectively.

The utilization of the heat from the motor exhaust within the blades of the propeller first, prevents snow and ice from lodging thereon; second, induces a scavenging action upon the said exhaust; and thirdly, as before mentioned, tends to minimize the outward slip of the air under the wings.

60 65 While a certain preferred embodiment of

this device has been shown and described, it will be understood that changes in the form, arrangements, proportions and details thereof may be made, without departing from the scope of the invention as defined 70 by the appended claims.

Having described my invention what I desire to secure by Letters Patent and claim, is:—

1. A motor driven aeronautical propeller 75 comprising a plurality of blades, and means for conveying waste gases from the motor to said blades and causing them to issue transversely thereof, whereby the gases act as a barrier against the radial flow of the 80 air under the blades.

2. A motor driven aeronautical propeller comprising plural blades, and means for leading the exhaust gases from the motor to issue arcuately adjacent to the outer edges 85 of said blades so as to minimize the outward slip of the air thereunder.

3. A motor driven aeronautical propeller comprising blades, and means extending at different levels relatively to said blades for 90 passing the products of combustion from the motor to the perimetral edges thereof, said means being provided at substantially right angles to said edges with orifices through which said gases are caused to issue. 95

4. A motor driven aeronautical propeller comprising one or more blades, and means for heating the same by conducting in proximity thereto the burnt gases from the motor, said means enabling the gases to issue 100 circumferentially of the blade or blades whereby the rotary motion of the latter creates a drawing action tending to scavenge the motor.

5. A motor driven aeronautical propeller 105 comprising a hollow shaft connected with the exhaust from the motor, tubular members communicating with said shaft, and opposed blades on said members acted upon by the burnt gases during their discharge. 110

6. A motor driven aeronautical propeller comprising a hollow shaft adapted to receive the exhaust gases from the motor, tubular members communicating with said shaft and provided with perforations at 115 their outer ends, and chambered blades carried by said members taking over their perforated portions and having orifices for the discharge of the gases.

7. A motor driven aeronautical propeller 120 comprising a hollow shaft adapted to receive the exhaust gases from the motor, recessed elements carried in spaced relation upon said shaft, and communicating with the interior thereof, tubular members supported by said elements in communication with the recesses in the latter, and chambered blades including discharge orifices, said blades being mounted upon the outer ends 125 of said members, said ends of the members 130

having perforations enabling the gases to pass into said blades in advance of their exit through the orifices.

8. An aeronautical propeller including a shaft, elements mounted in spaced relation on the latter, arms held in pairs by said elements at different distances from said shaft, and opposed blades supported upon the outer portions of said arms.

10. 9. An aeronautical propeller including a shaft having spaced lower and upper portions of different sizes, an element formed with carriers offset from said shaft, said element being affixed to the lower portion of the latter, another element provided with carriers fixed to the upper portion of the shaft adjacent to the axis thereof, arms extending in opposite directions from the carriers of both said elements, and opposed blades joining the upper with the lower ones of said arms.

10. An aeronautical propeller including a shaft, lower and upper elements mounted in spaced relation on the latter, sockets formed with said elements at different distances from said shaft, the sockets on the lower element being offset from the shaft while the sockets on the upper element are located adjacent to the axis thereof, sets of arms extending in opposite directions from the sockets of both elements, and opposed blades joining the lower with the upper sets of said arms.

11. An aeronautical propeller including a shaft, lower and upper elements spaced axially on the latter, pairs of arms extending in opposite directions from said elements, the lower pair of said arms being offset substantially tangentially to said shaft while the upper arms pass closely to the axis thereof, and opposed blades joining the lower with the upper pairs of arms.

12. An aeronautical propeller including a shaft, opposed blades carried from the latter, said blades having leading and trailing edges disposed substantially diametral to and tangentially offset from said shaft respectively, and guys extending convergingly from said blades to the shaft and also at right angles thereto.

13. An aeronautical propeller including a shaft, lower and upper carriers spaced upon the latter, pairs of arms projecting tangentially outward from said carriers in

opposite directions, the lower pair of said arms being offset from said shaft while the upper pair is adjacent to the axis thereof, opposed blades supported by said pairs of arms, and guys extending from said blades to a point on the shaft downwardly beneath the lower carrier and also to the outer portions of the carrier last named.

14. An aeronautical propeller including a shaft, lower and upper carriers spaced axially thereupon, sockets formed with said carriers, the sockets on the lower carrier being offset from said shaft while the sockets on the upper carrier are disposed adjacent thereto, arms projecting tangentially outward from said sockets in opposite directions, opposed blades mounted on said arms, anchoring means fastened to the shaft beneath the lower carrier, and guys extending from said means to the under side of said blades, some of said guys converging forward from their respective points of attachment on the lower portions of the blades downwardly to the anchoring means, other guys running from the same points of attachment horizontally forward to the sockets of the lower carriers, and certain other guys converging from the upper portions of the blades downwardly to the anchoring means in a rearward direction.

15. An aeronautical propeller including a shaft with shoulder portions spaced apart from one end thereof, a carrier element secured upon the outer one of said portions, a larger carrier element attached to the inner shoulder portion, a set of members supported in tangential relation by the smaller element adjacent to said shaft, another set of members also held tangentially to the latter at a distance therefrom by the larger element, and blades sustained conjointly by said members.

16. An aeronautical propeller including a shaft, a set of members extending tangentially thereto in opposite directions, means for supporting said members one on each side of said shaft at a distance therefrom, a second set of members projecting oppositely from the shaft, other means on the latter carrying said second set of members diagonally in offset relation to the first named set, and blades joining both sets of members.

ROBERT WILLIAM DAVIS.
